UNITED STATES PATENT OFFICE

FERDINAND E. FICK, OF SOUTH EUCLID, OHIO

SNOWPLOW

Application filed May 28, 1928. Serial No. 280,973.

This invention relates broadly to portable hand-operated implements, and more specifically to apparatus of the type adapted for use in the removal of snow or other relatively light, loose comminuted material.

One of the objects of this invention is to construct an implement which may be pushed or shoved over uneven, irregular surfaces, such as the furrowed path of a driveway or 10 the undulated surface of a sidewalk which is formed of broken flagstones or slag.

Another object of this invention is to provide a light portable implement for the translocation of snow, or similar light, loose material, which may be readily adjusted to cut a furrow of the desired depth thru the material.

Another object of the invention is to provide an implement for the removal of snow, 20 which may be expeditiously operated under variable conditions and which furthermore will eliminate the arduous labor of lifting and throwing the material as is necessitated in the customary usage of a snow shovel or 25 scoop.

Another object of the invention is to construct a light, portable appliance, durable of construction and economic of manufacture.

Other objects more or less ancillary of the 30 foregoing and the manner in which all the various objects are realized will appear in the following description which, considered in connection with the accompanying drawings, sets forth the preferred embodiment of 35 the invention.

In the drawings—

Fig. 1 is a view in perspective illustrating the general construction of the preferred embodiment of the invention;

Fig. 2 is a detail view in section, shown upon an enlarged scale, the section being taken on a plane indicated by the line 2—2 in Fig. 1;

Figs. 3, 4 and 5 are fragmentary, sectional views, similar to a portion of the detail shown in Fig. 2 and illustrative of alternate methods of securing the snow plow share with the frame.

Fig. 6 is a view in perspective illustrating

an alternative form of construction of the plow-share.

Fig. 7 is a transverse sectional view taken on a plane indicated by the line 8—8 in Figure 7.

Referring to the construction illustrated in Fig. 1 the implement in its entirety comprises but two members, a frame 10 and a plate or plow-share 11. The frame as illustrated is constructed from a single strip of thin walled pipe or tubing which is formed with a looped or transversely bent, central portion 12, linear side rails 13, and similarly substantially arcuated terminating end sections 14. These end sections are bowed or bent upwardly, divergent to the plane common to the side rails and looped end of the frame, and are extended through an arc of substantially 90°.

The plate 11 is supported upon the linear portions of the frame 10 and is preferably longitudinally adjustable therewith. In the instant case the lateral edges of the plate are folded over the side rails 13 and are frictionally engaged thereby through the inherent resiliency of the frame which may be formed slightly divergent, with respect to its major axis, in its unstressed form. The upper edge of the plate or plow-share 11 is provided with a handle for the convenience of the operator in raising or lowering the share. This handle may be of any suitable construction such as the aperture 15 herein illustrated.

In Figure 3 an alternate lock is illustrated which comprises a dowel pin 19 suitably attached to the outer wall of the frame and positioned for reentrant engagement with one of a series of apertures 20 in the folded edge portion of the plate. The apertures 20 in this embodiment are arranged in the plane traversed by the side rails when the free ends of the frame are sprung towards each other.

A frictional clamping mechanism is illustrated in Fig. 4, this embodiment contemplating the securing of the plate upon the frame by the distortive influence of a clamping nut 21 retained upon a bolt 21^a which passes through aligned holes 22 drilled in the plate 11.

Another alternative clamping mechanism

is shown in Fig. 5 wherein the plate 11 is provided with bolts 24, cooperatively associated with angle clamps 25 and nuts 26, which are capable of adjustment to effect the retention of the plate upon the frame side rails 13.

5 The plate or plow-share 11 may be constructed in various forms to accommodate its use with the variable adaptations to which the implement is susceptible. In Figures 6 and 7 10 an angulated plate 27 is shown which is particularly adapted to deflect the snow to the sides of the pathway rather than to accumulate the same upon the face of the plate. The configuration of the plow-share in this case is 15 preferably formed so that the lower edge 28 may be parallel with the plane of the surface over which it is translated under normal working conditions and adapted to engage the surface of the ground over which it is traversed.

20 In the operation of this implement the plow-share is first vertically adjusted upon the frame to cut a furrow or path through the drifted areas or to remove a limited portion 25 of the upper surface of a heavy, evenly distributed snow fall. As the coating of snow upon the path is cut away the share may be 30 adjusted into intimate association with the floor of the path, obviously this adjustment being concurrent with the irregularities of the surface of the path or driveway.

35 Utilizing the looped portions 12 of the frame as a handle the operator may push the implement before him, adapting the upturned arcuated end sections of the plow frame as 40 runners which will cut their way through the snow and glide over irregularities in the ground. The loaded plate may be dumped by diverting the plow from the course of the pathway and then tilting it forward or, in the form having the plate retained by the 45 resilient frame, by drawing the plate upwardly upon the frame so as to effect the discharge of the load by gravity.

50 Although the foregoing description is necessarily of a detailed character, in order that the invention may be completely set forth, it is to be understood that the specific terminology is not intended to be restrictive or confining, and that various rearrangements 55 of parts and modifications of structural detail, such as the substitution of heterogeneous side rails for the looped frame member or the transposition of the plate upon the frame, may be resorted to without departing from the scope or spirit of the invention as herein claimed.

What I claim is:

60 1. An implement comprising a looped frame having substantially arcuated free ends, a plate slidably engaged upon linear portions of the said frame and means for retaining the plate upon the frame.

65 2. A snow plow embodying a frame member and a plow-share, the said frame member

having arcuated runners formed at its lower end, and clamping means to facilitate the affixture of the two members.

3. An implement comprising an inherently resilient looped frame, a plate slidably supported thereby and retained thereon by the frictional engagement of the stressed frame.

4. A portable snow plow embodying a frame having lineal portions formed from a continuous strip of tubing, a plate having folded marginal edges supported thereon by the engagement of said folded marginal edges with said linear portions of the frame.

5. A portable implement for removing snow comprising a frame formed from a continuous strip of tubing, the said strip being formed in an open loop with upturned terminating ends, a plate supported upon the said frame above its upturned portions, and adjustably secured thereon.

6. A portable snow plow comprising a pair of substantially parallel frame side members having arcuated terminating ends, a plate having its lateral edges conformable with the contour of the said side members, and enveloping at least 180° of the periphery of each side member.

7. An implement for the removal of snow comprising spaced frame members, having arcuated free ends, a plate supported thereby, and means for adjusting the said plate longitudinally with respect to the arcuated free ends of the said frame members.

8. An implement embodying a frame formed from a continuous strip of metal, a plate mounted thereon and longitudinally adjustable thereon, and runners formed at the lower end of said frame.

In testimony whereof I hereunto affix my signature this 17th day of May, 1928.

FERDINAND E. FICK.
